Des. 214,336
Patented June 3, 1969

214,336

WATCHBAND ATTACHMENT

Patrick Petrie, 12210 Malone St.,
Los Angeles, Calif. 90066

Filed Mar. 27, 1967, Ser. No. 6,388

Term of patent 14 years

Int. Cl. D11—01

U.S. Cl. D45—4

FIG. 1

FIG. 2

The drawing is lined for color contrast.

I claim:

The ornamental design for a watchband attachment, substantially as shown and described.
